UNITED STATES PATENT OFFICE.

SVEN JULIUS STRID, OF CHICAGO, ILLINOIS, ASSIGNOR TO FRED MATHEWS, OF CHICAGO, ILLINOIS.

MOUNTING FOR BRAKE GEAR.

Application filed April 9, 1926. Serial No. 100,889.

My present invention relates to the manner of mounting a railway car hand-brake at the end of the car. Specifically my improvements relate to the installation of a 5 brake-gear housing at the end of the car in a manner so that the housing is dependably reinforced and braced to prevent vertical deflection of the horizontally disposed members of the structure under the stress of 10 the pull of the chain incident to applying the brakes. In certain types of all-metal freight-cars, the end-sills or car end-members are frequently metal stampings and are 15 insufficiently braced or reinforced to withstand the pull of hand-brakes that have been designed for the purpose of creating increased power, and when such gearings are installed it becomes necessary to provide structures in 20 addition to what is found upon the car in order to prevent deflection of the gear-housing and the parts of the car to which the housing is connected.

It is the purpose of my present invention to provide a reinforcement adapted for the 25 foregoing purpose, which reinforcement embodies compactness in arrangement, dependability in operation, economy in manufacture, and novelty in construction. I prefer to carry out my invention and to accomplish the several objects thereof in substantially the manner hereinafter fully described and as more particularly pointed out in the claims, reference being made to the accompanying drawings that form a part of this specification.

In the drawings:

Figure 1 is a top plan of a portion of the 35 end of a rail-way car showing my improvements installed thereon.

Figure 2 is a longitudinal side elevation of the 40 structure illustrated in Figure 1 with portions of the end of the car in transverse section.

Figure 3 is an outside end elevation of the 45 structure illustrated in Figure 1.

Figure 4 is a view similar to Figure 2 of a slightly modified construction.

Figure 5 is a perspective of the upper portion 50 of one of the brace elements employed in the aforesaid structures.

Figure 6 is a perspective on a reduced scale of the metal stamping end-member employed in the structures shown in Figures 1, 2, and 3.

The drawings, which are somewhat sche-

matic, illustrate typical or preferred forms 55 in which my improvements may be fabricated, and in said drawings similar reference characters have been employed to designate the same parts wherever they appear throughout the several views. 60

In Figures 1, 2, and 3 of the drawings is shown a car end in which the vertical end-wall 10 of the body has the bottom or floor 11 secured to its lower edge portion, and to its exterior face is secured an angle-metal mean or sill of Z-shape transverse section disposed with its web portion 12 in a horizontal plane with one of its flanges 13 vertically disposed alongside the wall 10 and riveted to it, and with its other flange 14 disposed vertically pendent at the outer edge of the web and below the lower edge of the wall. Secured to the lower portion of the end of the car is an angular metal stamping which extends downwardly a suitable distance to 75 provide a support for the gear-housing and it is herein illustrated in two forms. In both forms, the stamping has upper and lower horizontally disposed flanges or plates 15 and 16 respectively that are connected at 80 their edges by a transverse vertically disposed web 17 disposed in the vertical plane that is spaced from but parallel with the vertical plane of the end-wall 10. In the structure shown in Figure 4, this stamping 85 is elongated in a horizontal direction so that it extends substantially the width of the end of the car in the form of an end-member or sill and has its upper plate or flange 15 extended underneath the end of 90 the car body and riveted or otherwise secured to the bottom or floor plate 11. In some instances it is neither necessary nor desirable to employ the elongated end-member stamping just described, in which event 95 this member may be shortened to the proportions illustrated in Figures 1, 2 and 3, and utilized in conjunction with an angular metal end-sill such as herein disclosed. When the shorter metal stamping is employed it is preferably of box-like form for 100 greater strength and it is therefore provided with end walls 18 that connect the edges of the vertical web and the top and bottom flanges of the end-member and for the purpose of rigidity the top flange and the web are fitted into the corner formed by the horizontal web 12 and outer vertical 105

flange 14 of the sill member of which they are respectively secured by rivets or otherwise.

The hand-brake of the car is operated by means of a gearing that is connected with the lower end of mast 19 and may be of any desired type, and for this purpose I have schematically shown herein a gearing of well-known construction. This gearing is preferably mounted within a housing consisting of top and bottom castings the latter including a horizontally disposed plate 20 with upstanding side-walls 21 that are spaced apart horizontally a distance sufficient to be secured to corresponding side-walls 22 depending from a somewhat rectangular shaped top plate 23 that is spaced above and parallel with the bottom plate to permit the gears to be rotatably mounted between them. The top plate 23 of the housing is positioned against the underneath surface of the lower horizontal flange 16 of the metal hereinbefore described and it is riveted or otherwise secured thereto and extends inwardly to a point back of the vertical plane of the end wall 10 of the car. The opposite portion of the top plate 23 projects beyond the vertical plane of the web 17 of the metal stamping and is provided with an upstanding lug or stop 24 that is elongated in the direction of the length of the web 17 of the metal stamping and is secured thereto in any suitable manner.

35 The pull of the brake-chain when the gears are operating during the application of the brake has a tendency to tilt or deflect the housing which of course might distort the metal stamping and in order to reinforce the structure I have provided a suitable brace at the inner portion of the housing which will transmit the stress to more rigid portions of the car. This brace I prefer to form from a short 40 piece of U-shaped channel-bar that is positioned with its web 25 and its parallel flanges 26 all in vertical planes and disposed so that said channel-bar extends between the inner portion of the top plate 23 of the housing and the overlapped portions of the floor 11 and the flange 15 of the metal-stamping. For the purpose of connecting the brace to the top plate, the latter is provided with an upstanding flange 27 that 45 fits against and is secured to the lower portion of the web 25 of the brace and which is disposed in a plane transverse to the plane of the stop 24 and at substantially a right angle thereto. The upper portion of the 50 brace is connected to the floor or bottom plate 11 and the top horizontal flange of the metal stamping by means of a lateral lug 28 that is riveted to one or both of the aforesaid parts, and is formed by cutting away portions of the flanges and web of

the brace and bending the remaining free portion of the web laterally to its main portion either in the direction in which the flanges project or oppositely thereto as indicated respectively in Figs. 1, 2, and 3 and 70 in Figs. 4 and 5.

From the foregoing it will be seen the gear-housing is connected in a rigid manner to the end portion of the car by means of a mounting structure that is dependable 75 in preventing the housing from tilting or being accidentally moved out of its intended position when the brakes are applied, and it also avoids distortion of the end member which is a sheet metal plate stamped 80 the desired shape as indicated. Other specific modifications of the structure may readily be made for the purpose of adapting the same to cars having different construction, and it will be understood that such changes are included within the scope of the appended claims.

What I claim is:—

1. A mounting for brake-gears comprising a member at the end of the car having a vertical web and horizontal upper and lower flanges, a gear-housing secured to the lower flange of said member and extended inwardly of the car, and means for bracing the inner portion of said housing against 95 the upper flange of said member.

2. A mounting for brake-gears comprising a member at the end of the car having a vertical web and horizontal upper and lower flanges the former of which is secured to the car body to position said member below the car body, a gear-housing secured to the lower flange of said member and extended inwardly of the car, and means for bracing the inner portion of said housing 100 against the upper flange of said member.

3. A mounting for brake-gears comprising a member at the end of the car having a vertical web and horizontal upper and lower flanges the former of which is secured to the car body to position said member below the car body, a gear-housing secured to the lower flange of said member and extended inwardly of the car, and a vertical 110 brace extending between the inner portion of said housing and the upper flange of said member to the respective elements, whereby to brace the inner portion of said housing against said upper flange.

4. A mounting for brake-gears comprising a member at the end of the car having a vertical web and horizontal upper and lower flanges and secured pendent to the lower portion of the car body, a gear-housing secured to the lower flange of said member and extended inwardly of the car, and a brace secured at its lower end to the inner portion of said housing and at its upper end secured to the overlapped portions of the car body and the other flange of said member. 125 130

5. A mounting for brake-gears comprising a member at the end of the car having a vertical web and horizontal upper and lower flanges, a gear-housing disposed below the car body and secured to said member, an upstanding lug upon the inner portion of said housing, and a brace connected to said lug and extended to an upper horizontal portion of the car end structure and secured thereto.

10 6. A mounting for brake-gears comprising a member at the end of the car having a vertical web and horizontal upper and lower flanges, a gear-housing disposed below the car body and secured to said member, an upstanding lug upon the inner portion of said housing, and an angle-metal bar secured at its lower end to said lug and at its upper end to the end of the car.

15 7. A mounting for brake-gears comprising a member at the end of the car having a vertical web and an upper flange that is secured to the end of the car, a gear-housing disposed below the end of the car, a stop on said housing secured to the web of said member, an upstanding lug on the inner portion

of said housing, and means connected to said lug and extended to an upper horizontal portion of the car end structure and secured thereto.

20 8. A mounting for brake-gears comprising a member at the end of the car having a vertical web and an upper flange that is secured to the end of the car, a gear-housing disposed below the end of the car, two elements projecting upwardly from the top of said housing in spaced relation to each other, one of said elements secured to the web of said member and the other element connected with the portion of the upper flange that is secured to the car.

25 9. A mounting for brake-gears comprising a boxlike member formed from a sheet metal stamping secured to the end of the car, a gear-housing secured to a lower portion of said member, and means bracing the inner portion of said housing against an upper horizontal portion of said member.

30 Signed at Chicago, in the county of Cook, and State of Illinois, this first day of April, 1926.

35 40 45 50 SVEN JULIUS STRID.
